(57) **CLAIM**

I claim the ornamental design for a cooling plate, as shown and described.

DESCRIPTION

FIG. 1 shows a perspective view of the cooling plate.

FIG. 2 is a plan view of the cooling plate.

FIG. 3 is a side elevation view looking from the left side of FIG. 1.

FIG. 4 is a front elevation view of the cooling plate.

FIG. 5 is an elevation view looking from the right side of FIG. 1.

FIG. 6 is a rear elevation view.

FIG. 7 is a bottom plan view of the cooling plate; and,
FIG. 8 is a bottom perspective view looking from the rear of the view shown in FIG. 1.
